TOOL SHARPENING DEVICE

Ralph Maze, Hollister, Calif.

Application July 31, 1934, Serial No. 737,758

2 Claims. (Cl. 76—82)

It is one object of the present invention to provide a device whereby a tool may be immovably supported at a desired angle for the sharpening operation.

5 It is another object to provide a device capable of providing rigid support for various tools such as axes, hoes, chisels and knives.

It is still another object to provide a device wherein the tool may be fixedly supported at the 10 desired angle for sharpening, and also wherein a file may be slidably supported in operative relation to the cutting edge of the said tool.

It is still a further object to provide means 15 whereby the cutting angle of the file may be quickly and easily adjusted to the edge of the tool.

Finally it is an object of the invention to provide means of the character indicated that will be economical to manufacture, simple in form 20 and construction, that consists of few parts, that will be strong and durable, and highly efficient in its practical application.

In the drawings:

Figure 1 is a perspective view of one form of 25 the invention as adapted for use in sharpening a hand axe.

Figure 2 is a perspective view showing the manner in which a file is mounted for use in connection with a tool holder such as shown in Figure 1.

30 Figure 3 is a perspective view of the holder provided with adaptors to be used in sharpening tools such as a chisel and garden hoe, parts being broken away.

Figure 4 is a perspective view of a portion of 35 the hoe sharpening adapter shown in Figure 3.

Figure 5 is a perspective view of an adaptor for use in sharpening a knife such as a carving knife, a part being broken away.

In the particular embodiment of the invention 40 herein disclosed I show at 1 a plate having one end bent back upon itself as at 2 to form a channel 3, and having its opposite, or front, end turned upwardly as at 4. The part 4 has a recess 5 formed in the center of its upper edge, and has 45 an upwardly and inwardly extending socket as 6 formed in each side edge. Mounted on each side edge of the plate and intermediate its ends are upstanding arms as 7 carrying an upstanding plate as 8, the lower edge of the plate, as 9, being 50 spaced from the plate 1 as shown. At 10 are shown a series of holes formed in plate 8 and disposed in a line midway between arms 7 and extending from its bottom edge 9 to its top.

At 11—11 are two wires twisted together at 55 one end as at 12 and bent into a U shape so that

when the twisted end is inserted in a hole 10 the free end portions will straddle the part 4 and be readily brought into engagement with the sockets 6, the wire being resilient. A strap is shown at 13 bent around one wire part 11 to slidably engage the same and extending across the device and under the other wire portion 11.

If, now, an ordinary hand ax is to be sharpened the head, shown partially at 14, is placed on plate 1 with its cutting edge overlying the top 10 edge of part 4 and the other end seated on part 1 and against part 8. The holder 11—12—13 is now placed thereon with the end 12 inserted in a hole 10 and the free end portions 11—11 sprung into sockets 6.

With the holder mounted as described the strap 13 contacts the full width of the axe head yet the wire ends may be readily spread to engage the sockets.

At 15 is a small U shaped element having a 20 set-screw 16 mounted therein, thereby forming a clamp to fasten on the blunt end of a file 17 as shown. Extending from the clamp and in axial alignment with the file is a rod 18. Mounted on the clamp and held in place by the screw 25 16 is a plate 19, this plate having a flange 20 provided with a hole 21 through which the rod 18 passes. The flange 20 serves to reinforce the plate 19.

When the axe is placed and secured as above 30 described the rod 18 is inserted in one of the holes 10 and the file brought into contact with the edge of the axe. The file may now be swung along the full length of the edge of the axe, swinging about its engagement with hole 10 as 35 a pivot. The dotted line 22 indicates the center line of the rod 18 and the file 17, and the arc 23 indicates the direction of movement of the file when in operation. While the file is being manipulated as above described by one hand, the other 40 hand of the operator may be brought to bear upon plate 19 in order to secure the desired cutting pressure.

If a chisel is to be sharpened, then an adapter is used. One form of adapter is shown in Figure 45 3 where an L shaped member 24 is seated on plate 1 and against plate 8. A socket 25 is formed on the front of member 24 and disposed to receive the butt end of the chisel which is then placed with its cutting edge in the recess 5 and 50 held and sharpened in the manner hereinbefore described.

To sharpen a hoe, a supporting member as 26 is provided, this member having end portions as 27 bent back upon itself to form channels as 28 55

adapted to slidably engage the side edges of part 4. The member 26 is provided with two symmetrically disposed ears 29, spaced as shown and disposed to form a seat for the blade of the hoe. 5 The blade is supported by fingers 30 forming sockets as 31 and mounted on the rear face of the ears as shown. For supporting the handle of the hoe I provide an extension 32 projecting forwardly and downwardly from the front of the 10 plate 1, and having a block 33 disposed on its forward end, the said block having a recess 34 formed therein to receive the hoe handle. At 35 is shown a hook mounted on extension 32 by means of a strong spring 36 and so disposed that 15 when the hoe is in position the hook may be moved into engagement with the handle and cooperate with the ears 29 and block 33 to hold the hoe immovably in position. When so held the hoe may be sharpened in the manner here- 20 inbefore described.

A knife may be sharpened in the manner described by providing a special holder such as shown in Figure 5. This holder comprises a plate or member 37 having channels as 38 formed on 25 its side edges to slidably engage the side edges of part 4. The upper portion of the member is inclined forwardly as shown at 39, each end having a strap as 40 bent back to overlie part 39 and formed into a socket as 41 to receive and support 30 the knife blade.

It is to be understood, of course, that while I have herein shown and described certain specific embodiments of the invention, changes in form, construction, and method of assembly and ap-

plication, changes may be made within the scope of the appended claims.

I claim:

1. A tool holder comprising a plate, a fixed up- 5 standing member thereon provided with upwardly spaced holes, an upstanding flange formed thereon in spaced and parallel relation to the fixed member, and having notches formed in its side edges, a U shaped wire member engageable with one of said holes at its closed end and hav- 10 ing its open end engageable with said notches, a plate disposed transversely of said wire member, said plate being mounted on one wire portion and passing under the other, and a file holding device engageable with one of the holes in 15 the first mentioned fixed upstanding member and swingable over the upstanding flange.

2. A device of the character described comprising, a pair of fixed upstanding spaced and parallel members, one member being disposed to engage and support the cutting edge of an ax head and having stops disposed at either side edge thereof, and the second member extending above the first and having vertically spaced means associated therewith for slidably engaging a file 25 holder, a U shaped resilient member having means on its closed end to engage the second member and having its side portions disposed to engage said stops, an element disposed transversely of 30 said side portions to receive the downward thrust thereof, and a file holding device engageable with the second upstanding member and swingable over the first member.

RALPH MAZE.
